REARWARDLY STRIKING FIRING
MECHANISM

George Norman Albree, Winchester, Mass.

Application August 22, 1944, Serial No. 550,578

17 Claims. (Cl. 42—69)

1
This invention relates to firearms and particularly to firearms designed for rim fire ammunition.

One of the principal objects of the invention is to provide an improved firearm of this type in which the detonation of the rim fire cartridge is produced by the impact of the firer element (which may be in the form of a firing pin) against the front face of the cartridge rim, and by the term "front face" I mean the side of the cartridge rim of a chambered cartridge that faces toward the front of the gun as distinguished from that side of the cartridge rim which forms part of the end face of the cartridge.

In detonating any rim fire cartridge, the rim of the cartridge must be backed up by an anvil element when the detonating impact is made by the firing pin or other firer element, and in the conventional firearm for use with rim fire ammunition, the chambered end of the barrel constitutes the anvil member and it backs up the front face of the rim of the cartridge while the detonating impact of the firing pin is made against the rear face of the cartridge.

In my invention the breech block or bolt constitutes the anvil member of the firing mechanism and it is therefore a combined breech closure and anvil member. The detonation of the cartridge is secured by the impact of a rearwardly directed firer element against the front face of the rim of the cartridge, the rear face of said rim and the head of the cartridge being solidly backed up by the combined breech closure and anvil element at the time of such impact.

Another object of my invention is to provide a firearm in which the firing pin is disassociated from the breech block or bolt so that it is possible to use a bolt having a flat face unbroken by any aperture or opening to accommodate the firing pin to back up the head end of the cartridge when the latter is fired.

Still other objects of the invention are to provide a firearm with means for securing controlled ignition and thereby greater accuracy; to provide a novel firearm having dual or multiple ignition, thereby reducing the chance of misfire; to provide a firearm of simplified construction, and otherwise to improve firearms in the particulars hereinafter set forth.

In order to illustrate the invention, I have

2
shown in the drawings two different embodiments thereof, one of which involves a fixed firing pin, and the other of which involves a movable firing pin.

5 In the embodiment having a fixed firing pin, the firing pin is located at the end of the barrel adjacent the breech and in position to engage the front face of the cartridge rim as the latter is delivered into the chamber of the barrel. The forward movement of the bolt by which a cartridge is delivered from the magazine into the chamber of the barrel forces the front face of the rim against the firing pin with sufficient impact to cause detonation of the priming material 15 in the rim of the cartridge, so that the cartridge is actually fired by its movement into the chamber of the barrel. There are certain advantages resulting from this operation which will be more fully hereinafter set forth.

20 In the case of the movable firing pin said pin is located so that it is in front of the front face of the rim of the cartridge and a suitable means is provided whereby, when the trigger is squeezed, the firing pin will be brought into engagement 25 with the front face of the cartridge rim with a hammer-like blow sufficient to detonate the priming in the cartridge. In this embodiment of the invention the bolt or breech block provides a solid backing for the head of the cartridge when the 30 firing pin strikes the front face of the rim.

The invention can be embodied in either so-called "single shot" firearms or in firearms which are either semi-automatic or full automatic or both.

35 In the drawings, wherein I have illustrated two embodiments of my invention,

Fig. 1 is a side view of a firearm embodying the invention;

Fig. 2 is a fragmentary longitudinal section 40 through the firearm shown in Fig. 1;

Fig. 3 is an enlarged partial section on the line 3—3, Fig. 1;

Fig. 4 is an enlarged partial section on the line 4—4, Fig. 2;

45 Fig. 5 is an enlarged partial section on the line 5—5, Fig. 2;

Fig. 6 is a side view of the insert which carries the fixed firing pin or pins, said figure also illustrating the manner in which the rim fire cartridge is detonated thereby.

Fig. 7 is a side view of a firearm of the "Bullette" type embodying my invention;

Fig. 8 is a fragmentary sectional view of the firearm shown in Fig. 8 illustrating the movable firing pin and the mechanism for actuating it;

Fig. 9 is a section on the line 9—9, Fig. 8.

Referring first to Figs. 1-6, 1 indicates the stock of the firearm, 2 the barrel, 3 the receiver, and 4 the bolt which is backed by the usual action spring 17. The barrel 2 is mounted in the receiver in any suitable way and is provided at its rear end with the usual chamber 5 for receiving the cartridge 6, the bore 7 of the barrel being provided with the usual rifling, not shown. The firearm shown in Figs. 1 and 2 is a magazine firearm and is equipped with a removable magazine 8 of any usual construction which receives a plurality of rim fire cartridges 6 and which delivers said cartridges successively into the position shown in Fig. 2. In said Fig. 2 the bolt 4 is shown in its retracted or cocked position, in which position it is held by the sear 9, the end 10 of which is adapted to engage a shoulder 11 with which the bolt is provided. The sear 9 may have any suitable or usual construction and that herein shown is similar to the sear and trigger action used in the well-known "Springfield" rifle. The sear is shown as pivoted to the receiver at 12 and is acted upon by a spring 13 which normally tends to throw the end 10 of the sear upwardly. The trigger 14 is pivoted to the sear as shown at 15 and the cammed upper end 16 of the trigger bears against the under side of the receiver as shown at 16. With this construction, when the trigger is pulled, the camming action of the part 16 of said trigger against the under side of the receiver will swing the sear downwardly about its pivot, thereby releasing the point 10 from the shoulder 11 of the bolt, thus allowing the bolt to be driven forward by the action spring 17.

This action is illustrated herein because it is simple and effective, but any other suitable action, may be employed in connection with my invention.

The spring 17 is shown as encircling a pin 18 that is mounted in the removable head 19 of the receiver. When the bolt is in its open or retracted position, the front end of the pin 18 extends into an axial chamber 20 with which the bolt is provided, said pin preferably having a running fit in said chamber. The front end of the bolt 4 is shown as having a flat under face which rests and slides on a block 21 with which the receiver is provided.

The bolt 4 is provided with a transversely extending pin or handle 47 which projects through a slot 51 formed in the receiver. This pin or handle provides means by which the bolt can be manually operated, and it also provides means for locking the bolt either in a retracted position or a closed position.

The pin 47 is provided with a collar 48 and the bolt 4 is provided with a recess 49 of a size to receive said collar 48. The engagement of the collar with the receiver limits the movement of the pin to the right in Fig. 3 and the recess of the pin to be moved inwardly or to the left in Fig. 3.

At the opposite side of the receiver from that at which the pin 47 projects, said receiver is provided with two spaced apertures, one of which is indicated at 52 and is situated opposite the left-hand end of the slot 51, while the other aperture 52a, which is indicated by dotted lines in

Fig. 2, is situated opposite the right-hand end of said slot 51, each aperture being of a size to receive the end of the pin 47. When the bolt is in its cocked position shown in Fig. 2 the end of the pin 47 is situated almost but not quite in line with the aperture 52. The end of the pin is rounded as shown so that when the bolt is in cocked position, it is possible to force the pin 47 inwardly or to the left, thus camming the end thereof into the aperture 52. This operation serves to retract the bolt slightly and to lock the bolt just back of its cocked position.

The aperture 52a in the receiver is so situated that it is in register with the pin 47 when the bolt is in its forward or closed position and there is no cartridge in the chamber 5. When these conditions exist, then the pin 47 can be moved inwardly to enter the end thereof into the opening 52a, thereby locking the bolt in its forward position.

If there is a cartridge in the chamber, the bolt cannot be moved forwardly into a position which will permit the pin 47 to enter the aperture 52a, and therefore, by easing the bolt forward and then testing the pin 47, it is possible to tell whether or not there is a cartridge in the chamber. This testing of the locking pin can readily be accomplished in the dark, and this construction, therefore, constitutes a valuable safety feature of the invention.

In this embodiment of the invention the firer (that is the element which detonates the cartridge by pinching the rim of the cartridge against the anvil element, and which is frequently in the form of a firing pin) is fixed in position and is located at 21 and projects rearwardly from the breech end of the barrel 2 in position to engage the front face of the rim of the cartridge when the latter is driven into the chamber 5 of the barrel by the bolt. While the firer or firing pin may be provided for in various ways, yet I prefer to make it as an integral part of a bushing 21 that is inserted in an axial recess 22 with which the rear end of the barrel 2 is provided. This bushing 21 is provided on its rear face with a rearwardly extending projection 23 (see Fig. 6) which constitutes the firer. Any number of these firer projections may be employed, but I have herein illustrated two of them which are situated diametrically opposite each other. The contact faces of the firer may have any desired circumferential dimension. These firer or firing pins are located flush with the bore through the bushing 21, which bore constitutes a part of the wall of the cartridge-receiving chamber 5. The front face 24 of the bolt, which constitutes the anvil element is solid and it is preferably provided with a shallow recess 25 of the size to receive the rim of the cartridge.

As stated above Fig. 2 shows the bolt in retracted or cocked position. When the trigger 14 is squeezed the sear 9 will be disengaged from the shoulder 11 of the bolt, and the latter will be quickly driven forward by the spring 17. As the bolt moves forward, it strips the top cartridge 6 from the upper end of the magazine 8 and feeds said cartridge into the chamber 5 of the barrel. The movement of the bolt 4, due to the action of the spring 17, is an accelerating movement, and during the final forward movement of said bolt the rim 26 of the cartridge is suddenly pinched between the firing element or elements 23 and the front face of the combined bolt and anvil member. The impact between the front face 27 of the cartridge rim and the firing pin or pins is sufficient

to detonate the priming material in the rim of the cartridge. The dimensions of the fixed firing pin or pins will preferably be such that during the final forward movement of the bolt the cartridge rim 26 will be suddenly squeezed together at the points where the firing pin or pins engage it sufficiently to detonate the fulminate in the cartridge.

The gas pressure developed by the firing of the cartridge will not only drive the bullet or projectile 80 through the bore of the barrel but the back pressure will also move the bolt backwardly into its rearward position, thereby compressing the spring 17 as usual in automatic firearms.

If the pressure on the trigger is maintained so that the sear 9 is held in an inoperative position, then the firearm will operate as a full automatic weapon, the bolt being forced backwardly into its retracted position as each cartridge is fired, and then immediately being driven forward again by the spring 17, thereby stripping the next cartridge from the magazine 8, delivering it to the chamber 5 of the barrel and producing detonation of said cartridge by impact of the firing pin or pins 23 against the front face 27 of the cartridge rim. This automatic action will continue as long as the pressure on the trigger is maintained and any cartridges remain in the magazine.

If the trigger is released as soon as it has been pressed, the return of the sear to its operative position by the spring 13 will bring the nose 10 thereof into position to engage the shoulder 11 of the bolt as the latter is forced backwardly, thereby holding it in its rearward or cocked position.

It is understood that the firearm will be provided with the usual extractor 28 and the usual ejector 29. These elements are not shown in detail herein because they form no part of the present invention and any suitable extractor or ejector may be used.

The operation of a firearm having the construction above described is as follows. It will be noted that the weapon fires when the bolt goes forward, that is, the detonation of the cartridge is accomplished during the final forward movement of the bolt. For this reason it is important that the bolt should not be allowed to go home while the loaded magazine is in operative position, unless it is desired that the gun should be discharged.

The magazine 8 is removable to permit it to be reloaded or replaced by a filled one. Before a 50 filled magazine has been inserted into operative position, it is desirable to try the bolt operation and trigger action by grasping the pin or handle 47 and then pressing the trigger and easing the bolt forward to its closed position. The loaded magazine can then be inserted into its chamber from below where it will be securely held by the usual magazine lock which may be released by pressing the button 70. Any suitable magazine lock may be used, and therefore, it has not been 60 thought necessary to illustrate one. The bolt 4 should then be drawn back by the handle 47 as far as it will go. As the bolt reaches a rearward position, the point 10 of the sear will be automatically moved up into its operative position in front of shoulder or bent 11. The firearm is then cocked ready to fire. The pressing of the trigger 14 depresses the sear 9 and allows the bolt 4 to drive forward under the pressure of the recoil spring 17. During its forward movement, the bottom lip of the bolt face strips the top round 6 from the magazine 8 and as said bolt pushes the cartridge forward and into the chamber the head of the cartridge slides up the smooth face of the bolt 70 behind the extractor 28 and becomes seated in the 75

recess 25 of the bolt. As the cartridge is driven forward with accelerating speed, the front face of the rim 26 containing the priming material is suddenly stopped by the protruding firing pins 23. During the final forward movement of the bolt into closed position, the rim 26 of the cartridge is pinched between the face of the bolt and the firing pins 23 and the cartridge is thereby detonated.

Ignition takes place while the bolt is still moving forward so that at the instant of detonation of the cartridge the back pressure is against a bolt which has not entirely come to rest.

The gas pressure developed by ignition applies a forward force on the bullet which drives it through the bore of the barrel and also a backward pressure on the bolt, but since the weight and consequently the inertia of the bullet is only a small fraction of that of the bolt, the bullet will be discharged from the barrel before the pressure in the barrel has overcome the inertia of the bolt and started it backwards. During the backward movement of the bolt the extractor 28 withdraws the empty case from the chamber, and as said case encounters the ejector 29 it is hurled from the gun through the ejection port 74.

This cycle of operation continues as long as the trigger is held back and there are any cartridges in the magazine. If, however, pressure on the trigger is removed the sear will again engage the bolt, thereby holding it back in operative position so that bursts of two or three shots may be obtained by simply tapping the trigger. Upon the last shot being fired, the bolt is held open, which will allow air circulation through the barrel between bursts.

It will be noted that the rear portion of the bolt contains an axial bore 20 adapted, when the bolt is moved into its rearward position, to receive the end of the pin 18 which is secured to the head 19. When the end of the pin 18 enters the bore 20 during the backward movement of the bolt, the air which is thus trapped in the bore 20 becomes compressed and forms an effective air break or buffer for cushioning the backward movement of the bolt. This compressed air augments the action of the recoil spring 17 in starting the bolt on its return forward trip.

One advantage of using two or more firing pins is that the chances of a misfire is greatly reduced. In the conventional firearm for rim fire ammunition which has a single firing pin, it may happen that when the trigger is pressed the firing pin will strike a portion of the rim of a cartridge which, by reason of a defect in manufacture, has an insufficient amount of priming material to produce detonation, thereby causing misfire.

With two or more firing elements, this chance of misfire is very greatly reduced and practically nullified.

Moreover by having a plurality of firing pins which are symmetrically disposed, the impact of the firing pins against the rim of the cartridge is balanced throughout the area of said rim.

Where the firing pins are carried by a bushing such as shown at 21 in Figs. 4 and 6 it is possible to make this bushing removable or interchangeable so that bushings having firing pins with larger or smaller contact faces may be employed depending upon the make of ammunition which is being used. Some makes of ammunition may operate more satisfactorily with firing pins having relatively large contact faces, while another make of ammunition may operate more

successfully when firing pins having a relatively small contact face are employed. By using such removable and interchangeable bushings it is possible to easily and speedily equip the firearm with firing pins having the proper size to fit the particular ammunition which is being used. This feature of the invention, therefore, provides means for readily controlling the ignition of the ammunition.

In the construction shown in Figs. 7, 8, and 9 in which the firing element is in the form of a movable firing pin 1a indicates the stock, 2a the barrel, 3a the receiver, and 4a the combined bolt and anvil member. The barrel is provided with the chamber 5a to receive the cartridge 6 and the bore of the barrel is shown as having the usual rifling 7a.

In this embodiment of the invention the firing pin is indicated at 28a, and it is illustrated as pivoted at 29a to the receiver 3a, the receiver and the end of the barrel being provided with a slot 30 in which the firing pin operates. This slot, however, does not break into the chamber 5 of the barrel.

At its upper end the firing pin has a short projection 31 situated to engage and deliver a detonating impact against the front face 27 of the cartridge rim 26, the head of the cartridge being at the time solidly backed by the end face of the combined bolt and anvil member 4a. While any suitable means may be employed for delivering a hammer-like blow to the firing pin for the purpose of causing it to produce a detonating impact against the front face of the cartridge rim, yet I have herein shown for this purpose a hammer element 32 which is slidably mounted in a bore 33 with which the barrel is provided and which extends parallel to the rifled bore 7a of the barrel.

This hammer element 33 is backed by a spring 34 which is confined in the end 35 of the bore 33. The hammer is normally held in its retracted or cocked position by means of a suitable sear which in turn is released by pressure applied to the trigger 14a. Any suitable trigger and sear mechanism may be employed for this purpose and it will be understood that when the trigger is squeezed and the sear releases the hammer, the latter will be moved toward the firing pin by the spring 35 and will deliver a hammer-like blow against the upper end of the firing pin thereby causing the latter to have its detonating impact against the front face 27 of the cartridge rim 26.

The sear herein illustrated is indicated at 9a and it is provided with a nose 36 adapted to engage a shoulder 37 with which the hammer element 32 is provided. The sear is normally held in its operative position shown in Fig. 8 by some suitable spring means, and a suitable connection between the trigger 14a and the sear is provided by which backward swinging movement of the trigger will move the sear downwardly out of engagement with the shoulder 37.

In the particular construction illustrated the sear is formed with a resilient stem portion 38, the end 39 of which is anchored to the barrel by screws 40. The resiliency of the stem 38 tends to move the sear 9a upwardly into its operative position but permits the sear to be moved downwardly for releasing the hammer 32.

In the construction herein shown the trigger 14a is pivoted at 41 to a post 42 which is secured at its upper end to the barrel 2a and the upper end of the trigger is connected to the sear by a link 43 one end of which is pivoted to the trig-

ger at 44 and the other end of which is pivoted to the sear at 45. A backward swinging movement of the trigger will operate through the link 43 to move the sear downwardly as above described. This post 42 is shown as bifurcated and the upper end of the trigger, the link 43 and the end portion of the sear are received in the slot 46 formed by the bifurcation of said post.

I have herein illustrated the hammer 32 as being provided with a shoulder 37 at each end, thus making it reversible so that in assembling the firearm either end of the hammer may be inserted into the bore 33. If desired the bore 33 may be vented to permit free movement of the hammer. Any suitable or usual means may be employed for cocking the hammer element 33, such for instance as a pin (not shown) similar to the pin 47 by which the bolt 4 is cocked, and which may be anchored to the hammer element and operate in and project through a slot with which the stock 1a may be provided.

In the type of firearm shown in Fig. 7, the magazine, indicated at 8a, is in the butt end of the stock.

Both forms of the invention as herein illustrated comprise a combined bolt or breech closure and anvil member and also comprise a rearwardly directed firer element situated in front of the combined breech closure and anvil member and in position to engage the front face of the rim of a rim fire cartridge occupying the firing chamber thereby to pinch said rim against the combined breech closure and anvil member with the result that the cartridge will be detonated.

35 I claim:

1. A firearm of the rim fire type, comprising a barrel having a firing chamber, an anvil member in the rear of the barrel to engage the end of a rim fire cartridge occupying the firing chamber, and means for detonating said cartridge in said firing chamber, said means including a firing element situated in front of the anvil member to engage with the front face of the rim of said cartridge thereby to pinch said rim against the anvil.

2. A firearm of the rim fire type, comprising a barrel having a firing chamber, an anvil member separate from the barrel situated in the rear thereof, said anvil member having a smooth unbroken face for engagement with the end face of a rim fire cartridge occupying the firing chamber, a firing element situated in front of the anvil member, and means to cause said firing element to engage the front face of the rim of said cartridge and pinch it against the anvil member, thereby to detonate the cartridge.

3. A firearm for a standard rim fire cartridge comprising a barrel having a firing chamber, a combined breech closure and anvil member, a firing pin situated in front of the combined breech closure and anvil member, and means to cause the firing pin to engage the front face of the rim of a rim fire cartridge occupying said firing chamber and to pinch said rim against the combined breech closure and anvil member thereby to fire the cartridge.

4. A firearm for a rim fire cartridge comprising a barrel, a firing pin situated in front of the front face of the rim of a rim fire cartridge which has been loaded into the barrel, an anvil member situated in the rear of the firing pin and forming a backing for the head of said cartridge, and means to cause the firing pin to produce a detonating impact against said front face of the car-

tridge rim while the cartridge is backed by anvil member.

5. A firearm for a rim fire cartridge comprising a barrel having a firing chamber, a rearwardly directed firing pin carried by the barrel and situated to engage the front face of the rim of a rim fire cartridge occupying the firing chamber, a combined bolt and anvil member to engage the head end of said cartridge, and means to produce a detonating impact of the firing pin against said front face of the cartridge rim while the end of the cartridge is engaged by the combined bolt and anvil member.

6. A firearm of the rim fire type comprising a barrel having a cartridge-receiving chamber, a combined bolt and anvil member for engaging the end of a rim fire cartridge and feeding it into said chamber, and a firing pin carried by the barrel and situated to engage the front face of the rim of said rim fire cartridge during the final movement thereof into said chamber by the combined bolt and anvil member, whereby the rim of the cartridge is pinched between the firing pin and said combined bolt and anvil member, and the cartridge is detonated.

7. A firearm for a rim fire cartridge comprising a barrel having a cartridge-receiving chamber, a combined bolt and anvil member for feeding a rim fire cartridge into said chamber, and a fixed rearwardly directed firing pin carried by the barrel and situated to engage the front face of the rim of such cartridge during its final movement into said chamber by the combined bolt and anvil member, whereby said rim is pinched between the firing pin and the bolt and the cartridge is detonated.

8. A firearm for a rim fire cartridge comprising a barrel having a cartridge-receiving chamber, an anvil member engaging the end of a rim fire cartridge occupying said chamber, a movable firing pin situated to engage the front face of the rim of said cartridge, and means to give said firing pin a detonating impact against said front face while the anvil member is in engagement with the end of said cartridge.

9. A firearm for a rim fire cartridge comprising a barrel having a cartridge-receiving chamber, an abutment member engaging the end of a rim fire cartridge occupying said chamber, a movable firing pin situated to engage the front face of the rim of said cartridge, a spring-impelled hammer carried by the barrel for giving the firing pin a detonating impact, and trigger means to control the release of the hammer.

10. A firearm for a rim fire cartridge comprising a barrel having a cartridge-receiving chamber and a recess at its breech end, an abutment member for engaging the end of a rim fire cartridge when it is in said chamber, a movable firing pin occupying the recess of the barrel and adapted to engage the front face of the rim of said cartridge, and means to give said firing pin a detonating impact against said front face.

11. A firearm for a rim fire cartridge comprising a barrel having a cartridge-receiving chamber and a rifled bore leading therefrom, and also having a second bore open at its breech end and extending parallel to the rifled bore, an abutment member engaging the end of a rim fire cartridge when it is in said chamber, a movable firing pin situated to engage the front face of the rim of said cartridge, a spring impelled hammer carried in said second bore and adapted to give the firing pin a detonating impact, and trigger means to control the release of the hammer.

12. A firearm for a rim fire cartridge comprising a barrel having a cartridge-receiving chamber, a bolt for feeding a rim fire cartridge into said chamber, and a plurality of rearwardly directed firing pins carried by the barrel and each adapted to engage the front face of the rim of a rim fire cartridge which is being fed into said chamber by the bolt and during the final bolt-actuated movement of said cartridge into said chamber, thereby to cause detonation of the cartridge.

13. A firearm for a rim fire cartridge comprising a barrel having a cartridge-receiving chamber, a bolt for feeding a rim fire cartridge into said chamber, and two rearwardly directed firing pins carried by the barrel and situated diametrically opposite each other, each firing pin being situated to engage the front face of the rim of a rim fire cartridge while it is being fed into said chamber and during the final movement of the cartridge into said chamber, thereby to cause detonation of the cartridge.

14. A firearm of the rim fire type having a barrel provided with a firing chamber, a reciprocating bolt for feeding rim fire cartridges to the firing chamber, said bolt constituting an anvil member, a plurality of cartridge firers distributed uniformly around the mouth of the firing chamber for engagement with the front of the rim of a rim fire cartridge occupying said chamber to pinch the rim against the face of the bolt, whereby the bolt face may be flat and the base of the cartridge may seat against the flat bolt face in transit to the firing chamber without danger of premature firing.

15. A firearm of the rim fire type having a barrel provided with a firing chamber, a reciprocating bolt for feeding rim fire cartridges to the firing chamber, said bolt constituting an anvil member, a cartridge firer adjacent the mouth of the firing chamber for engagement with the front face of the rim of a rim fire cartridge occupying said chamber to pinch the rim against the face of the bolt, the cartridge firer comprising a projection fast to the wall of the firing chamber and projecting rearwardly therefrom.

16. A firearm of the rim fire type having a barrel provided with a firing chamber, a reciprocating bolt for feeding rim fire cartridges to the firing chamber, said bolt constituting an anvil member, a cartridge firer adjacent the mouth of the firing chamber for engagement with the front face of the rim of a rim fire cartridge occupying said chamber to pinch the rim against the face of the bolt, the cartridge firer comprising a striker movable to the rear after a cartridge is seated in the firing chamber.

17. A firearm of the rim fire type comprising a barrel having a firing chamber, a combined breech closure and anvil member situated in the rear of the barrel, said member having a flat unbroken face free from protuberances for engagement with the end face of a rim fire cartridge occupying the firing chamber, a rearwardly directed firing element situated in front of the combined breech closure and anvil member, and means to cause said firing element to have a detonating impact against the front face of the rim of said cartridge while the latter is backed solidly by the combined breech closure and anvil member thereby to detonate the cartridge.

GEORGE NORMAN ALBREE.
